TOY AIRPLANE

Leon C. Wallace, 2483 South Fourth East,
Salt Lake City, Utah 84115

Filed Dec. 16, 1968, Ser. No. 14,987

Term of patent 14 years

Int. Cl. D21—01

U.S. Cl. D34—15

FIG. 1.

FIG. 2.

FIG. 3.

FIG. 4.

FIG. 1 is a front perspective view of a toy airplane showing my new design;

FIG. 2, a top plan view;

FIG. 3, a side elevation view; and

FIG. 4, a front elevation view.

The broken line showing of a tether line is for illustrative purposes only.

I claim:

The ornamental design for a toy airplane, substantially as shown and described.
